ELECTRIC FRYING PAN

Donald William Morphy, Chislehurst, England, assignor to Morphy-Richards Limited, Kent, England

Filed Oct. 14, 1958, Ser. No. 52,978

Term of patent 14 years

(Cl. D81—10)

Fig. 1 is a top perspective view of an electric frying pan embodying my new design;

Fig. 2 is a bottom perspective view thereof illustrating the side and end opposite those shown in Fig. 1;

Fig. 3 is a side elevation; and

Fig. 4 is a bottom plan view thereof.

I claim:

The ornamental design for an electric frying pan, as shown.
